DESIGN FOR A CIGARETTE DISPENSER

Martin Satloff, Brooklyn, N. Y.

Application July 23, 1946, Serial No. 131,856

Term of patent 14 years

(Cl. D85—2)

To all whom it may concern:

Be it known that I, Martin Satloff, a citizen of the United States, residing in the city of Brooklyn, county of Kings, State of New York, have invented a new, original, and ornamental Design for Cigarette Dispensers, of which the following is a specification, reference being had to the accompanying drawing, forming part thereof.

The figure on the drawing is an isometric view of a cigarette dispenser showing my new design.

I claim:

The ornamental design for a cigarette dispenser, as shown.

MARTIN SATLOFF.
